UNITED STATES PATENT OFFICE.

ALBERT E. MAYNARD, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

BEVEL-EDGING MACHINE.

Application filed May 28, 1924. Serial No. 716,423.

The present invention relates to ophthalmic lens edging machines and has particular reference to a bevel edging machine.

An important object of the invention is to provide a bevel edging machine embodying a grinding element, means to rotate the grinding element, a lens holding element, means to rotate the same, means to compensate for displacement due to change in plane of lens as it rotates, a shape controlling pattern, means to regulate the size of the shape, means to feed the lens and lens carriage toward the stone step by step, means to stop the feed and to rotate the lens several times without the feed to give the final grinding motion to throw the lens holder away from the stone, and means to stop the rotation of the lens.

Another very important object of the invention is to provide a bevel edging machine that will grind both surfaces of a lens simultaneously, the said machine including a stone having a substantially V shaped groove formed therein, the said stone being mounted on a rotary shaft by means of a flexible connection and means for holding and rotating the lens in the groove whereby the stone mounting will be moved torsionally to accommodate for displacements due to the various changes in plane of the lens as it rotates.

A still further object of the invention is to provide a bevel machine including a rotary stone shaft and a rotary lens clamping shaft, neither one of which is movable relative to the other during the grinding operation.

Other objects and advantages of the invention will become apparent during the course of the following description.

In the drawings, wherein like numerals are employed to designate like parts throughout the same:

Figure 1 is a front elevation of my improved machine.

Figure 2 is a side elevation thereof.

Figure 3 is a detail elevation illustrating the step by step controlling mechanism.

Figure 4 is a side elevation of one form of stone mounting employed.

Figure 5 is a section taken on line 5—5 in Figure 4.

Figure 6 is a side elevation of a slightly different form of stone mounting employing the same principle.

Figure 7 is a section taken on lines 7—7 in Figure 6.

Figure 8 is a side elevation of a slightly modified form of stone mounting.

Figure 9 is a section taken on line 9—9 in Figure 8.

Figure 10 is a similar section showing a modified construction.

Figure 11 is a side elevation of still another form of stone mounting.

Figure 12 is a section taken on line 12—12 thereof.

Figure 13 is a fragmentary sectional detail of a slightly modified form of mounting shown in Figure 12.

Figure 14 is a sectional view showing the relation of a plano lens to my form of stone mounting.

Figure 15 is a top plan view of the initial position of the stone and lenses of the convex and concave type.

Figure 16 is a view of a lens.

Figure 17 is a view similar to Figure 15 showing the action of the stone upon a partial rotation of the lens.

Figure 18 shows a still further step in the rotation of the lens clearly illustrating the twisting movement upon the shaft and stone.

Figure 19 is a modified form of lens clamp.

Prior to this invention many attempts have been made to bevel both surfaces of an ophthalmic lens simultaneously. The chief difficulty has been that the finished lens has not measured up to standard size. For instance a minus 8 diopter lens and a positive 8 diopter lens have been ground on the same machine with the same setting, one after the other, and after being measured it has been found that there was nearly two millimeters difference in the size of the two lenses. In other words, the lenses were ground on a machine with the shape and the size control mechanism untouched during the grinding of the two lenses and upon examination the lenses did not measure to standard size. One of the lenses was approximately one millimeter under size while the other of the said lenses was approximately one millimeter over size. As far as can be ascertained, this same difficulty of grinding either under size or over size lenses has been met with on all machines employing either an axially movable stone or an axially movable lens carriage.

In the present invention, I employ a stone which may be torsionally moved with respect to the stone shaft so that it will accommodate itself to the displacements caused by the difference or change in planes of the lens as it is rotated. By a torsional movement, I mean a stone which is adapted to be rocked and twisted with respect to its drive shaft or axis so that points of the periphery may be so arranged that they will not fall in planes at right angles to the axis of rotation.

The main difference between my machine and the prior art constructions is that I employ a stone which may be torsionally moved while the prior art constructions used an axially movable stone. The axially movable stones or carriages may be moved transversely to the machine but prior to my invention no stone has ever been employed wherein the stone may follow the lateral displacement caused by the changes in planes in the lens being ground and also may be twisted at the same time to follow the exact curvature and angle of that portion of the lens within the groove at the time the stone is being moved.

In the drawings, wherein for the purposes of illustration I have shown a preferred embodiment of the invention the numeral 20 designates a grinding element used in accordance with my invention. The grinding element is shown in Figures 1, 2, 4 and 5 and comprises a preferably onepiece stone having a substantially V-shaped groove 21 formed in its periphery. The stone 20 is provided with an enlarged central opening in which is adapted to be mounted a flexible member 22 which is clamped to the inner periphery of the stone by the clamps 23 and to a drive shaft 24 by means of the clamps 25. The flexible member 22 may be of any desired material such as fabric, rubber composition or the like provided that the material will be sufficiently strong to support the stone 20 to rotate the same while at the same time it must be flexible enough to permit of the stone being rocked and twisted on the drive shaft 24. In other words, the flexible connecting means 22 must be of such a nature that the stone and stone mounting 22 may be twistingly moved to compensate for the lateral displacements caused by the rotation of the lens to be ground within the groove 21. Thus the stone 20 is mounted for a twisting movement and not adapted for an axial movement in view of the fact that the drive shaft 24 is rotatably mounted but not laterally movable. In other words, all movement of the stone 20 must be taken care of by the flexible connecting member 22 and not in any way by the drive shaft 24 except for the fact that the drive shaft 24 rotates the said stone through the clamping member 25 and connecting element 22. The drive shaft 24 is journaled in the bearings

26 supported on the frame 27. The pulley 28 is keyed to one end of the shaft to drive the same.

The form of lens carriage illustrated in the drawings is not absolutely necessary to the operation of my improved machine as the action of the stone and mounting would be the same in any case while the lens is held within the groove of the stone and rotated. I have, however, shown one form of lens carriage which may be used with satisfactory results.

The lens carriage comprises the casting 29 journaled through one end of which is the shaft 30 on which the said casting is pivotally and partially slidably mounted. The shaft 30 has at one end the gear 31 which meshes with one of a train of gears 32, the said train of gears 32 deriving power from the gear 33 which is keyed to the opposite end of the drive shaft 24. The casting also has journaled therethrough the opposed aligned shafts 34 and 35 respectively, the said shaft 34 being both rotatably and slidably mounted in the said casting while the shaft 30 is a drive shaft imparting rotary motion to the lens 36 which is adapted to be received within the groove in the stone, the said shaft not being laterally movable through the casting. The shaft 34 is connected with the rocker arm 37 which is pivoted on the post 38 while the opposite end thereof is pivoted to the plunger 39 which is received within the recess formed in the carriage in the end of which is disposed a coil spring 40. The operating lever 41 is adapted to slide the plunger 39 within its recess thus compressing the spring 40 at the same time the rocker arm 37 which will move the shaft 34 thus separating the two aligned shafts to allow of the insertion or removal of the lens 36 from between the pads 42 carried by the ends of the opposed shafts.

In order to rotate the opposed shafts 34 and 35 respectively, the gear 43 is carried by the outer end of the shaft 35 and meshes with the intermediate or idler gear 44 which in turn meshes with the gear 45 which is keyed to the sleeve 46, the said sleeve 46 being received on the shaft 30. Obviously, upon rotation of the shaft 30 through the train of gears 32, gear 31 on the shaft 30, the gear 45 at the opposite end thereof will likewise be rotated and through the idler 44 the gear 43 will be rotated, thus revolving the shafts 34 and 35 carrying the lens 36 to be ground. In order to rotate the sleeve 45 with the shaft 30 the clutch 47 designated in its entirety is provided and comprises a stationary section 48 keyed to the end of the shaft and a movable section 49 movable into and out of engagement with the stationary section 48, the said movable section being moved into and out of an operative position by means of a pivoted yoke 50. When the

two sections of the clutch are disengaged the operation of the lens clamping shafts will be stopped and when the sections are moved into engagement with each other the opposed shafts 34 and 35 will be rotated as above pointed out.

In order to regulate the shape of the lens being ground the former 51 is provided and is held in position by means of a lock nut 52.

10 Although in the present instance I have illustrated but a single former, a gang of formers may be provided if desired although the arrangement I have shown will prove entirely satisfactory as any shape of former may readily be placed in position upon the machine for cooperation with the contact shoe 53 which is carried by the screw threaded shaft 54. The micrometer adjustment 55 is provided to control the size of the shape 20 being ground, the size being indicated on the scale 56 on the micrometer adjustment.

The spring 57 is connected to the pivoted carriage 29 at one end and to a stationary portion of the frame 27 at the other end so

25 that the pivoted carriage will normally be urged toward the stone so that the lens 36 will be under spring tension when in the groove 21 of the stone 20. Likewise the former or pattern 51 which is carried by the 30 shaft 35 will contact with the shoe 53 and as in the case of elliptical or irregular shaped formers will cause the carriage to be moved to and from the stone so that the same shape of lens will be ground as the shape of the 35 former used. Therefore, the advance of the lens and carriage toward the stone will be determined by the rapidity with which the former contact shoe 53 is moved and to govern this movement I mount the contact shoe

40 53 on a pivoted carriage 58 which is rocked on the pin 59. The pivoted carriage 58 is provided with a lip 60 which is clearly shown in Figures 2 and 3 of the drawings and is so arranged that it is adapted to rest

45 upon a portion of the frame 27 in such a manner that movement thereof is restricted in that direction. In Figure 3 is shown in full lines the position of the pivoted carriage contact shoe and shape former when the lip 60 is not in engagement with the frame 27

50 and in dotted lines is illustrated the position of the carriage and other parts when the lips 60 are in contact with the frame. It is to be understood that it is the rocking movement of this carriage 58 that controls the advance or step-by-step feed of the lens toward the stone during the grinding operation and that when the lip 60 contacts with the frame the lens no longer advances toward the stone but

55 is held in one position and is allowed to rotate several times for the final finishing, shaping and grinding revolutions.

The advance of the lens toward the stone is controlled by the continuous curve cam 61 which is carried on the shaft 62. The cam

61 has the high spot 63 and the curve gradually comes toward the center of rotation of the shaft 62 until the smallest or lowest portion of the cam is at about 64. A hardened member 65 is carried by the pivoted carriage 70 58 and is adapted to ride upon the face of the cam as is clearly illustrated in Figure 3. When the hardened portion 65 is on the high spot 63 the lens carriage will be farthest away from the stone and as the cam 61 rotates the member 65 will ride down until the point 64 is reached, at which point the lip 60 will rest upon the frame and the cam and member 65 will no longer contact. During the time that the cam 64 is on the low spot the lens will be 80 permitted to rotate several times at this fixed spot so that the final finishing and shaping revolutions will take place, after which the member 65 will again ride upon the high spot thus throwing the lens away from the 85 stone.

In order to rotate the cam 61 the gear 66 is keyed on the shaft 62 and meshes with the gear 67 carried on the second shaft 68 which carries the gear 69 which meshes with the gear 70. The gear 70 is on the shaft 30 and therefore upon rotation of the said shaft the shaft 68 will be rotated thus causing the gear 67 to rotate the gear 66, thus operating the cam. This gear arrangement causes the cam to be rotated slowly and gradually from the high spot to the low spot.

To simplify the operation of the machine I provide in addition to the automatic throw-out means, an automatic clutch to stop the rotation of the lens clamping shafts immediately after the throw-out of the lens has taken place. This mechanism comprises a second cam 71 which is likewise keyed to the shaft 62.

The arm 72 having the contact pin 73 is keyed to the shaft 74 journaled through a portion of the machine and due to spring tension between the arm 72 and machine the contact pin 73 will at all times be held against the cam 71. Loosely mounted on the shaft 74 is a yoke 75 which has engagement by means of the pins 76 with a movable clutch section 49 and is adapted to control the throw of the movable clutch section into and out of engagement with the stationary clutch section. The spring pressed finger 76' is adapted to engage in an opening formed in the pivoted yoke 75. The spring pressed pin 76' is carried by the arm 77 keyed to the shaft 74 so that upon movement of the shaft 74 the arm 77 will be moved.

At the beginning of the grinding operation the pin 76' is disengaged from the yoke 75 and due to an internal spring the movable clutch is moved into engagement with the stationary section of the clutch and the lens carriage is rotated. As the cam 71 gradually rotates the arm 72 will be moved inwardly toward the lens until a point has

been reached when the spring pressed pin 76' will snap into place in the recess formed in the yoke 75 and when the cam reaches the high point and just passes over the same the 5 arm 72 will be snapped inwardly so that the pivoted yoke will cause the movable section of the clutch to become disengaged, thus stopping rotation of the machine.

In order to line the lens up with the groove 10 in the stone the pivoted lever 78 is carried by the frame 27 and has engagement with the pin 79 on the lens carriage 29. In view of the fact that the lens carriage 29 may be 15 slidably mounted on the rotatable shaft 30 upon manipulation of the lever 78, the lens and groove in the stone may be placed in perfect alignment. It is understood, however, that the lens carriage does not have any lateral movement during the grinding 20 operation but is merely moved laterally when placing the lens in position for grinding as just pointed out.

In Figures 14, 15, 17 and 18 is shown the action of the stone during the grinding operation. It is to be remembered that the lens to be ground is fed straight into the groove of the stone. In Figure 14 the lens 36 is a plano lens and obviously is in perfect alignment with the stone during the grinding 25 operation and the stone does not twist or tilt. In Figures 15, 17 and 18, however, a different type of lens 80 is being ground. In Figure 15 is shown the initial position of the lenses in which the stone is perfectly perpendicular. The type of lens herein shown 30 is a convex-concave lens of elliptical shape and as is clearly shown, the surfaces do not follow any single plane. In Figure 17 is shown the position of the stone upon a partial revolution of the lens within the groove, 35 illustrating that the same displacement of the stone takes place in the rear as at the front, that is, if the front of the stone is moved to the right or left $\frac{1}{16}$ of an inch caused by the displacement of the lens due to 40 changes in the plane of the lens upon rotation the rear of the stone at a point in the same axis as the front will likewise be moved $\frac{1}{16}$ of an inch. It is to be noted, however, 45 that the movement in the front is in the opposite direction to that in the back of the stone. In Figure 18 is still another position 50 of the stone upon rotation of the lens within the groove. In this position in addition to being moved in a longitudinal plane the 55 stone is also tilted from its vertical plane so that no two points in the periphery of the stone lie in the same plane at right angles to the axis of rotation of the stone. Figure 60 18 clearly shows the twisting movement of the stone during the grinding operation. It is due to this rocking and twisting movement of the stone that I am able to edge a lens satisfactorily, with the result that I get a 65 lens that is ground absolutely true to shape

and accurate in size. When employing the axially movable stone it is impossible to obtain the position of the stone as is shown in Figure 18, while with the stone having a flexible centre the displacements caused by 70 the change in plane of the lens immediately causes the stone to assume the required position to give an absolutely true reproduction of the form used and size required.

In Figures 6 and 7 is shown a slightly 75 modified form of flexible connecting means between the stone 20 and the shaft 24. In this instance spring means are employed and I preferably unite two spring sections to form a single unit 81. In other words, I 80 take two spring sections, clamp them back to back, and then securely clamp them to the shaft by means of the clamp 82 which is keyed to the shaft 24 and to the stone 20 by means of the clamps 83. The spring 85 sections being formed in this manner will have the tendency to counteract the action of the other spring section, thus normally holding the stone in vertical plane.

In Figures 8, 9 and 10, instead of a flexible fabric centre or flexible spring centre, I employ pivoted links. The links forming the chain 84 are supported at the hub 85 by means of the transversely arranged pins 86 while they are supported on the plates 87 by means of the adjustable screw threaded 90 shafts 88. The lock nuts 89 on the ends of the shafts 88 permit the adjustment of the links when in use. It will be seen that the shape of the plates 87 are such that a wrench 95 may be placed between the stone and the plates to facilitate adjustment. In Figure 10 the long link 90 is employed, being connected to the screw threaded shaft 88 and the pins 86 by the short links 91.

In Figure 11 the arms 92 clamp to the stone 20 by means of the clamps 93 and support the raceway 94 between which are the balls 95 which are adapted to rest upon the second raceway 96. A driver 97 carried by the shaft 24 causes the stone to be rotated with the shaft.

In Figure 12 is shown one method of honing the stones and includes a pair of plates 98 having the inwardly extending flanges 99 which are slidably mounted on the shaft 24. Normally, during the grinding operation, the plates 98 are slid away from the stone so as not to hinder the twisting movement thereof but when it is desired to hone the 110 stone the plates are moved toward each other until the stone is firmly clamped in position for honing. The form of hone I employ is preferably in a circular disk form 100 and has the bevel edge adapted to be received 115 within the groove 21 of the stone. The form of hone shown in Figure 12 is held between the opposed shafts 34 and 35 of the lens carriage in a similar manner to the lens 120 so that the hone is simply placed between the 125

pads 42 and the machine is set in operation until the hone has removed the required amount of material from the stone. The hone may then be removed from between the opposed shafts and it will be found that the faces of the groove 21 have been sufficiently smoothed for the edging of lenses. In Figure 13 is shown a double raceway 101 instead of the single raceway as in Figure 11.

In Figure 19 the lens carriage is adapted to be twistingly moved instead of the stone. Obviously the same result will be had when the lens is held in clamping means that may be twistingly moved to allow the lens to adapt itself within the groove of the stone used for the edging.

From the foregoing, it will be gathered that I have provided a bevel edging machine employing a stone that is mounted upon a rotatable shaft which is not allowed to move laterally. The lens to be ground is received within the substantially V-shaped grooved frame in the periphery of the stone.

25 Due to the flexible connecting means between the lens and lens drive shaft, the stone may rock and twist itself in a twisting movement to compensate for the displacements caused by the difference in plane 30 of the lens as it rotates in the groove. The stone rocks in opposite directions, that is to say, if the point contacting with the lens moves to the left, the diametrically opposed side of the stone will move to the right, and 35 vice versa as is clearly shown in Figure 18, but the stone will be tilted as well as rocked so that all the points in the periphery will fall in different planes not at right angles to the axis of rotation. This stone bevels the 40 edge of a lens absolutely true and accurate both as to shape and as to size, and in addition, the ridge between the two surfaces of the lens will be ordinarily in the middle so that the lens will present a neat appearance 45 when mounted in an eyeglass or spectacle mounting.

It is to be borne in mind that neither the lens carriage nor the stone shaft has any axial movement during the grinding operation and that all displacements caused by the rotation of the lens in the groove are taken care of by the twisting movement of the flexible center of the stone connecting the stone and the drive shaft.

55 The lens to be ground is gradually fed toward the stone until a certain point has been reached at which point it is held against further movement and allowed to rotate several times so as to give the final sizing and 60 finishing revolutions after which the lens is automatically moved away from the stone and the clutch automatically stops rotation thereof.

It is to be understood that the form of the invention herewith shown and described

is to be taken as the preferred embodiment of the same and that various changes in the shape, size and arrangement of the parts may be resorted to without departing from the spirit of the invention or the scope of the subjoined claims.

Referring more particularly to Figure 19, the numeral 102 designates a grinding element which is neither axially nor twistingly movable upon or with respect to its drive shaft. In the present instance I employ a lens holder 103 in its entirety, which is adapted to be twistingly moved by reason of the contact of the lens 104 within the groove of the grinding element 102. The lens holding element comprises the separable shafts 105 and 106, respectively, the shaft 105 being carried by a suitable spider or the like 107, which has connection with the flexible member 108. The flexible member 108 is centered in its center 109 on the shaft 110, which has at one end the drive pin 111 and at the opposite end, that is, the end disposed on the other side of the flexible center 108 the ball bearing 112. The roller bearing 112 is adapted to ride on the inside of the spider or cup 107, so that the lens will have a drive, while at the same time it may be twistingly moved. The opposite shaft 106 is provided with the universal joint 113 and the cam operating mechanism 114 adapted to separate the opposed shafts when it is desired to insert or remove a lens for edging.

It is clear that either the stone or the lens holder may be mounted to give this twisting movement, either one giving the same result, although I have shown the stone so mounted as my preferred arrangement. Furthermore, the form of lens carriage or holder employed is not essential to the operation of the machine, as it is not absolutely necessary to use a carriage employing the step by step feed, the kick back, or the automatic clutch for disengaging the clutch to stop rotation of the lens, as the same type of stone will work equally well with a lens holder for holding the lens in contact with the stone, a pattern to regulate the shape and size of the lens being edged, and means to hold the lens against the stone.

Furthermore, any type or shape of lens may readily be bevel edged on this type of machine. A toric lens has a different curve in the two major meridians so that the displacement of the stone will be the differences in planes of the lens at the ends of the meridians. The same holds true of a cylindrical lens, while planos and sphericals have the same curve in the two major meridians; hence there is no displacement between the two meridians, while in the torics and cylinders there is a displacement as the lens is rotated in the groove of the stone. It will be noted from inspection of Figure 18 that the

stone has a double displacement, that is, it is rocked or twisted in two planes at right angles to each other so that no two points of the periphery of the stone fall in a plane 5 at right angles to the axis of rotation.

Having thus described my invention, I claim:

1. In a lens edging machine, a grindstone shaft, an annular grindstone ring having a 10 groove in its grinding face, lens clamps holding a lens with its edge extending into the groove in the grindstone, means for rotating the shaft, means for rotating the lens clamps, and a flexible member connecting the 15 shaft and the grindstone annular ring whereby the engagement of the edge of the lens in the groove in the grindstone as it rotates therein will bend the flexible member to permit the grindstone to adjust itself to the 20 change of position caused by the change of plane of the point of contact of the edge of the lens as it rotates.
2. In a lens edging machine, a grindstone shaft, an annular grindstone ring having a 25 groove in its grinding face, lens clamps holding a lens with its edge extending into the groove in the grindstone, means for rotating the shaft, means for rotating the lens clamps, and a yieldable diaphragm plate connecting the shaft and the grindstone annular ring whereby the engagement of the edge of the lens in the groove in the grindstone as it rotates therein will bend the yieldable diaphragm plate to permit the grindstone to 30 35 adjust itself to the change of position caused by the change of plane of the point of contact of the edge of the lens as it rotates.
3. In a lens edging machine, a grindstone shaft, an annular grindstone ring having a 40 groove in its grinding face, lens clamps holding a lens with its edge extending into the groove in the grindstone, means for rotating

the shaft, means for rotating the lens clamps, and a fabric diaphragm connecting the shaft and the grindstone annular ring whereby the 45 engagement of the edge of the lens in the groove in the grindstone as it rotates therein will bend the fabric diaphragm to permit the grindstone to adjust itself to the change of position caused by the change of plane of 50 the point of contact of the edge of the lens as it rotates.

4. In a lens edging machine, a grindstone shaft, an annular grindstone ring having a 55 groove in its grinding face, lens clamps holding a lens with its edge extending into the groove in the grindstone, means for rotating the shaft, means for rotating the lens clamps, and a flexible member connecting the shaft and the grindstone annular ring whereby 60 the engagement of the edge of the lens in the groove in the grindstone as it rotates therein can twist the flexible member in more than one plane to permit the grindstone to adjust itself to the change of position caused by the 65 change of plane of the point of contact of the edge of the lens as it rotates.

5. In a lens edging machine, a shaft, a grinding element on the shaft having a 70 groove in its grinding face, a lens holding element for holding a lens with its edge projecting into the groove of the grinding element, a shaft on which it is mounted, means for rotating the elements, means for urging one element towards the other, and a flexible 75 member between one of the elements and its shaft whereby the engagement of the edge of the lens in the groove in the grinding element as it rotates therein will bend the flexible element to permit the grinding element 80 to adjust itself to the change of position caused by the change of plane of the point of contact of the edge of the lens as it rotates.

ALBERT E. MAYNARD.
